CLAIM

The ornamental design for a garment, as shown and described.

DESCRIPTION

FIG. 1 is a front perspective view of a garment showing my new design according to a first embodiment;

FIG. 2 is a front view thereof;

FIG. 3 is a top view thereof;

FIG. 4 is a front perspective view of a garment showing my new design according to a second embodiment;

FIG. 5 is a front view thereof; and,

FIG. 6 is a top view thereof.

The long-and-short broken lines form an unclaimed boundary around the claimed subject matter, do not exist in the article, and form no part of the claim. The even-length broken lines, which show the remainder of the article beyond the unclaimed boundary, are directed to environment, represent unclaimed subject matter, and form no part of the claimed design.
